UNITED STATES PATENT OFFICE.

PIERRE LOUBET, OF PARIS, FRANCE, ASSIGNOR TO SOCIÉTÉ: HUE FRÈRES ET LOUBET, OF PARIS, FRANCE, A FRENCH CORPORATION.

APPARATUS FOR UNDERGROUND PUMPING.

1,401,620.

Specification of Letters Patent. Patented Dec. 27, 1921.

Application filed July 20, 1920. Serial No. 397,744.

(GRANTED UNDER THE PROVISIONS OF THE ACT OF MARCH 3, 1921, 41 STAT. L., 1313.)

To all whom it may concern:

Be it known that I, PIERRE LOUBET, citizen of the French Republic, residing at Paris, Department of the Seine, in France, (and having P. O. address 12 Rue Victor Duruy, in the said city,) have invented certain new and useful Improvements in Apparatus for Underground Pumping, (for which I have filed application for Letters Patent in France 10 September 21, 1917, Patent No. 486,897, May 15, 1918,) and I do hereby declare the following to be a full, clear, and exact description of the invention, such as will enable others skilled in the art to which it appertains to make and use the same.

The invention has for its object to effect improvements in pumps and consists in an addition to the latter of a tube having a strainer which is situated some meters below 20 the stratum of water and is surrounded by a cylindrical layer of Loire sand which has been carefully washed, the object being to insure a constant supply from any underground water stratum, even when the pumping is interrupted, and also to purify the 25 water and render it potable.

The invention is described herewith in detail with reference to the accompanying drawing which shows diagrammatically by 30 way of example one form of construction of the pumping and filtering apparatus.

Figure 1 is a vertical section showing an auxiliary pump pipe installation below the water stratum.

Fig. 2 is a section on a large scale of a part of the two cylinders of the strainer.

The pump tube 1, provided with a non-return valve 2 located under the pump and above the level of the water stratum 3, has 40 attached to it a tube 4 which is sunk into the ground vertically to a certain depth below the water stratum. This tube 4, up to a certain distance above its lower end which is closed, is provided on its surface with 45 holes 5 the total area of which is at least equal to that of the section of the tube. The tube 4 also has attached to it by means of a stuffing box 6 a double strainer or superimposed sleeves perforated along their entire 50 surface with very fine holes on the outer sleeve 7 and with somewhat larger holes on the inner sleeve 8. The strainer is likewise inclosed at its lower end.

In the boring made in the ground 9 a

cylindrical and tubular layer of charcoal 10 55 is arranged vertically while another layer of charcoal 11 is placed at the bottom. Around the strainer and above it at 12 Loire sand which has been carefully washed is placed. Another layer of charcoal 13 is 60 placed on it and above this a layer of sand 14 up to the ordinary level of the water stratum, the upper part of the well shaft 15 being finally filled up with earth up to the non-return valve.

It is understood that the filtering layers of charcoal or any other appropriate material are only employed when the water is impure and it is desired to render it fit for consumption while in ordinary cases it suffices to fill the boring containing the pipe and the strainers with Loire sand.

The object of this arrangement is to secure a constant supply from an underground water stratum by means of a pump for 75 which the apparatus described forms an indispensable addition.

If for example the water stratum becomes exhausted at a certain moment, the apparatus nevertheless continues to operate in consequence of the large reserve column of water which, while it is being pumped out, permits the water stratum to regain its level. Further, the suction effect of the apparatus draws to the suction pipe all the water contained in the surrounding ground. The output is assisted by filling up the upper part of the well since the suction then produces a vacuum as in the case of a closed vessel.

Claims—

1. In a sunken well shaft or bore, the combination with a pump, of a filtering means comprising an outside shell of charcoal, a portion of sand filling substantially the lower part of said shell, an intermediate layer of charcoal, and a top filling of sand, a strainer embedded in said lower portion of sand comprising inner and outer perforated shells, an outlet or suction pipe extending downwardly through said shaft or bore and into said strainer and perforations in the lower end of said pipe.

2. In a sunken well shaft or bore having its major portion extending below the water strata, the combination with a pump, of a filtering means comprising an outside shell of charcoal positioned in said major portion, a supply of sand filling substantially the

lower part of said shell, an intermediate layer of charcoal, and a top filling of sand, a strainer embedded in said lower portion comprising inner and outer perforated shells, 5 an outlet or suction pipe extending downwardly through the major portion of said shaft or bore and into said strainer and perforations in the lower end of said pipe.

3. In a sunken well shaft or bore having 10 its major portion extending below the water strata and having its portion above said water strata substantially closed, the combination with a pump, of a porous filtering me-

dium positioned in said major portion, a strainer embedded in said filtering medium 15 at the lower end of said major portion, and an outlet or suction pipe extending downwardly through the closed upper end, and also through the major portion of said shaft or bore, and into said strainer.

In testimony whereof I affix my signature, 20 in presence of a witness.

PIERRE LOUBET.

Witness:

CLEMENT S. EDWARD.
